FIG. 1

FIG. 2

FIG. 3

FIG. 4

FIG. 5

FIGURE 1 is a top plan view of a top shield for a silo unloader embodying my new design;

FIGURE 2 is a perspective view taken from one side thereof, the broken-line representation of a silo unloader being for purposes of illustration only;

FIGURE 3 is a perspective view thereof taken from the side opposite that shown in FIGURE 2;

FIGURE 4 is a perspective view thereof taken from the top and left of FIGURES 1 and 2; and

FIGURE 5 is an enlarged fragmentary perspective view thereof taken from the left of FIGURE 3.

I claim:

The ornamental design for a top shield for a silo unloader, as shown and described.
